CLAIM

We claim the ornamental design for a seat with a pattern, as shown and described.

DESCRIPTION

FIG. 1 is a top plan view of a seat with a pattern; and, FIG. 2 is an enlarged detail view thereof; this perspective view is taken from the lower right area of the seat with a pattern of FIG. 1.

The dot dash broken line surrounding FIG. 1 depicts the boundaries of the claim and forms no part thereof. The dot dash broken line surrounding FIG. 2 depicts the boundaries of the detail area and forms no part of the claimed design.
